ATTORNEY

UNITED STATES PATENT OFFICE.

WILLIAM A. SUTTON, OF NEW YORK, N. Y.

SKATE.

SPECIFICATION forming part of Letters Patent No. 239,120, dated March 22, 1881.

Application filed December 20, 1880. (No model.)

To all whom it may concern:

Be it known that I, WILLIAM A. SUTTON, of the city, county, and State of New York, have invented certain new and useful Improvements in Skates, of which the following is a specification.

The object of this invention is to improve the skates of that class which are attached by means of leather straps to the boots in such a manner that the connection of the runner with the sole-plate is made in a very reliable but cheap and simple manner, and that the expense of this class of skates is considerably reduced.

15 The invention consists of the combination of the sole-plate with the runner by means of locking wedge pieces or keys, which are passed through the sole-plate and sprung in between the beveled faces of the arms or brackets of the runner, the upper ends of the brackets being notched at their exterior sides to form an intimate connection with the wood, while side lugs or guards of the keys prevent the lateral displacement of the bracket-arms.

20 25 In the accompanying drawings, Figure 1 represents a sectional side elevation of my improved skate; Fig. 2, a top view of the same. Figs. 3, 4, and 5 are respectively a side view, a vertical transverse section, and a bottom view of the wedge-keys by which the connection of the sole-plate and runner is established; and Fig. 6 is a detail horizontal section through the runner-bracket on line xx , Fig. 1.

30 35 Similar letters of reference indicate corresponding parts.

A in the drawings represents the sole-plate, which, in the cheaper kinds of skates, is made of wood, and attached by means of 40 leather straps, in connection with projecting heel and sole pins, to the shoe or boot.

The runner B is provided with pairs of bracket-arms C at the front and rear part of the runner, which arms support the sole-plate by shoulders aa . The inner faces, bb , of the bracket-arms C, above the shoulders aa , are in close proximity to each other and are beveled, as shown in Figs. 1 and 2.

45 50 The connection of the sole-plate A and runner B is established in a rigid and reliable manner by means of wedge-pieces D, which are cast in one piece with the disks d , that

carry the projecting heel and sole pins or teats d , as shown clearly in Figs. 3 and 4. The wedge pieces or keys D are passed through holes of the sole-plate A and driven in between the adjacent beveled faces b of the bracket-arms C, so as to spring the same apart by the tapering shanks of the keys and cause the exterior notched faces of the upper ends of the bracket-arms to adhere firmly to the wooden sole-plate A, as shown in Figs. 1 and 6. The tapering shanks of the wedge-keys D are provided at opposite sides with T-shaped guards e , which engage the sides of the upper ends of the bracket-arms C, so as to prevent their lateral displacement in the sole-plate. The wedge-keys D form in this manner a reliable lock-connection of sole-plate and runner, which has the advantage that each part may be separately finished, and finally the parts assembled by the simple connection of sole-plate, runner, and wedge-keys.

Having thus described my invention, I claim as new and desire to secure by Letters Patent—

1. As an improvement in skates, the combination of the sole-plate A and runner B, the latter having pairs of bracket-arms C, with locking wedge-keys D, which are passed through the sole-plate and sprung in between the adjacent faces of the bracket-arms, substantially as set forth.

2. As an improvement in skates, the combination of the sole-plate A and runner B, having sets of bracket-arms C, which are provided at their upper ends with inner beveled and outer notched faces, in combination with locking wedge-keys D, having top disks and side guards or projections, e , substantially as described.

3. In skates, a connecting wedge piece or key having a top plate, a flat tapering shank, and T-shaped side guards or projections, substantially as specified.

4. In testimony that I claim the foregoing as my invention I have signed my name, in presence of two witnesses, this 14th day of December, 1880.

WILLIAM A. SUTTON.
